COMBINATION BACKSTAY AND SHEET FOR SAILING VESSELS

Horace M. Dobbins, Charleston, S. C.

Application June 16, 1949, Serial No. 99,520

2 Claims. (Cl. 114—102)

1

This invention relates to a combination back-stay and sheet for sailing vessels.

It has been the custom to attach the back-stays independently to cleats fastened to the deck of a sailing vessel. The sheets are also connected independently to cleats or other means so that each of the back-stays and sheets must be manipulated independently for loosening a sheet or back-stay while tightening a cooperating stay and sheet when varying the position of a sail and the boom.

It is an object of the present invention to combine a back-stay and sheet in such a manner in connection with a windlass that the combined stays and sheets are wound on the windlass, the operation of the windlass and the shifting of the boom while stabilizing the position of said boom being accomplished by a single operator.

A further object of the invention is the provision of a back-stay forming a single line with a sheet at each side of a ship for shifting and controlling the position of a boom, the lines on both sides of the ship being wound on a windlass in one direction or released in the opposite direction for stabilizing the boom at all times, the lines being wound on the windlass in an orderly manner, thereby eliminating cleats and the loose ends of the lines on the deck of the ship; means being employed for retaining the windlass normally against rotation.

The invention is best understood from a consideration of the following detailed description in connection with the accompanying drawing, nevertheless it must be borne in mind that the invention is not confined to the disclosure but is susceptible of such changes and modifications as shall define no material departure from the salient features of the invention as expressed in the appended claims.

In the drawings:

Figure 1 is a plan view of the deck of a sailing vessel showing my arrangement of the combined stays and sheets;

Figure 2 is a side view of the sailing vessel with the combined stays and sheets in an operative position; and

Figure 3 is a view of the stern of the ship disclosing the arrangement of the stays and sheets on guiding pulleys.

Referring more particularly to the drawings, 10 designates a sailing vessel having a stern 11. A mast 12 rises from the deck 13 and is supported by stays 14, 15 and 16. The stays 15 and 16 in this particular instance have a special construction which will be described presently.

2

A boom 20 is provided at one end with a yoke or other device 21 connecting it with the mast so as to allow the boom to swing from side to side.

5 A stay 22 is secured in a well known manner to a truck 23 mounted adjacent the top of the mast 12 while the opposite end of the stay is secured to the outer end of the boom 20 as at 24 for support of the boom at a proper angle. A sail (not shown) is connected between the mast 10 and boom in the customary manner.

It will be noted from Figure 1 that the stay 15 forms a one-piece line with a sheet 25 where said sheet and stay are trained on and between pulleys 26 and 27 which are mounted on the deck 15 at one side of the ship. The sheet is carried over a pulley 26' which swings from an extension 21' projecting from the outer end of the boom. The sheet 25 is directed downwardly and trained on a pulley 28 which is mounted on the deck directly 20 below the pulley 26'.

25 A windlass designated generally by the numeral 29 includes a drum 30 and a crank 31 for rotating said drum, but if preferred, an electric motor may be employed for operating the windlass. A base 32, secured to the deck, supports the drum and crank. A brake device or other instrumentality (not shown) is employed in a well known manner for retaining the drum against rotation.

30 The stay 16 and sheet 33 forms a single line, the sheet 33 being trained through respective pulleys 34, 35, and 36 while the stay portion of the line is trained through a pulley 37. The sheets 25 and 33 have their free ends attached to the drum and are wound in one direction or released in the opposite direction of rotation of the drum.

The operation of my device is as follows:

When it is desired to shift the boom, the crank 31 is revolved in the direction indicated by the arrow in Figure 1 and the sheets 25 and 33 are wound on the drum 30. In this manner the sheets are retained on the drum in an orderly manner while the boom is shifted and held in a predetermined position at all times.

When it is desired to shift the boom in the opposite direction from that just described, the crank 31 is reversely rotated and the sheets 25 and 33 are unwound from the drum. Thus, it will be seen that the boom is maintained in a stabilized position at all times, whether the boom is aligned with the center of the ship or shifted to either side of said center.

When the boom is allowed to swing out to the port side, the stay on the starboard side is

drawn tight by the pressure of the wind on the sail and vice versa, releasing both sheet lines at the same time, tightening the one on the opposite side to which the boom is released and loosening the one on the side the boom goes out on so that it will not interfere with the boom and vice versa when the boom goes out to the starboard side.

What I claim:

1. In a sailing vessel having a mast, a pair of stays directed from the top of the mast to points on the deck at opposite sides of the vessel, a boom, means pivotally attaching the inner end of the boom to the mast, the free end of said boom terminating adjacent one end of the vessel, a sheet integral with each stay and disposed upon respective sides of the center line of the vessel, pulleys mounted on the deck and pulleys suspended from the free end of the boom for guiding the combined stays and sheets, a rotatable drum mounted on the deck, the free ends of both sheets being fastened to and coiled on the drum in one direction.

2. In a sailing vessel provided with a mast and boom having one end pivoted to said mast, a stay and a sheet combined to form a single line leading from the top of the mast to the free end of

the boom, a second stay and sheet combined to form a single line leading from the top of the mast to the free end of the boom, said combined stays and sheets being disposed on respective sides of the center line of the vessel, pulleys for guiding each combined stay and sheet close to the deck of said vessel, a rotatable drum mounted on the deck intermediate the ends of the boom, means for rotating the drum, and pulleys suspended from the free end of the boom for guiding the sheets from the first mentioned pulleys to the drum, rotation of the drum in either direction causing not only shifting of the boom but stabilizing the position of the boom at all times.

HORACE M. DOBBINS.
